Primary Examiner — Anhdao Doan(74) *Attorney, Agent, or Firm* — Banner & Witcoff, Ltd.(57) **CLAIM**

The ornamental design for a magnetic resonance tomography diagnosis apparatus, as shown and described.

DESCRIPTION

FIG. 1 is a front perspective view of a magnetic resonance tomography diagnosis apparatus, showing my new design; FIG. 2 is a rear perspective view thereof; FIG. 3 is a front elevational view thereof; FIG. 4 is a top plan view thereof; FIG. 5 is a left side elevational view thereof; FIG. 6 is a bottom plan view thereof; FIG. 7 is a right side elevational view thereof; FIG. 8 is a rear elevational view thereof; FIG. 9 is an enlarged cross sectional view thereof, taken along the line 9-9 in FIG. 3 with its internal mechanisms omitted; and,

FIG. 10 is an enlarged cross sectional view thereof, taken along the line 10-10 in FIG. 3 with its internal mechanisms omitted.

The broken lines are for illustrative purpose only and form no part of the claimed design.
